Patented Jan. 8, 1918.

Benjamin & Reynolds
By John S. Barker,
his Attorney.

UNITED STATES PATENT OFFICE.

BENJAMIN S. REYNOLDS, OF MADISON, WISCONSIN.

CONCRETE-MIXING MACHINE.

1,253,097.

Specification of Letters Patent.

Patented Jan. 8, 1918.

Application filed July 10, 1917. Serial No. 179,653.

To all whom it may concern:

Be it known that I, BENJAMIN S. REYNOLDS, a citizen of the United States, residing at Madison, in the county of Dane and 5 State of Wisconsin, have invented new and useful Improvements in Concrete-Mixing Machines, of which the following is a specification.

My invention relates to machines for mixing concrete and has for its object to produce a machine of this character of small capacity and that can be manufactured at low cost and is particularly adapted for use upon the farm and in connection with small 15 operations.

In the accompanying drawings Figure 1 is a side elevation, Fig. 2 a top plan view, and Fig. 3 an end view of a concrete mixing machine embodying my improvements.

20 Fig. 4 is a detail view illustrating the support for one of the bearing rollers.

Fig. 5 is an end view of the yoke frame.

In the drawings 2-2 indicate the side members of the supporting frame, which 25 are preferably X-shaped, and suitably braced as by the parts designated 3. In this frame, supported so as to be freely revolved about its longitudinal axis, is a container which is preferably a wooden barrel 4, water tight 30 and of suitable strength. A bevel gear ring 5 is secured to the circumference of the barrel, preferably a little to one side of its center and toward its open end. The barrel is supported in a tilting frame mounted in 35 the supporting frame of the machine. The tilting frame has a pair of trunnions 7-7 that are adapted to lie in the crotches of the upper portions of the X-shaped side frames 2-2, where they are supported and 40 turn, thus making it unnecessary to provide bearings for the trunnions, though the latter might be used under circumstances rendering them desirable. The trunnions are supported or carried by plates 8-8 to 45 which are secured a pair of rings 9-9', within which the barrel lies. These rings are of such size that there is a free space between them and the circumference of the barrel opposite where they lie. Secured to 50 the peripheries of and uniting the rings 9-9' are a set of brackets 10 in which are mounted bearing rollers 11 adapted to engage with the periphery of the barrel, and constituting the rolling supports therefor. 55 There are preferably four brackets and rollers—two above and two below the barrel

when it is in working position. A yoke, constituting part of the swinging frame in which the mixing barrel is mounted, extends 60 rearward from the ring 9 around the rear or closed end of the barrel, being formed preferably of a pair of metal bars, suitably bent to form the yoke, and designated 12-12', and a rear cross piece 13 uniting such bars. The crossbar 13 is represented 65 as being secured to the yoke bars 12 12' by bolts 23 and these pass through slots in the bar 13 permitting a limited adjustment of the bar as will be described. A bearing for the closed end of the barrel is arranged 70 on its axis of rotation, and consists preferably of a socket 14, secured to the cross piece 13 of the yoke of the tilting frame and consisting of two separable parts, adapted to be closed over the head or ball of a 75 piece 15, secured to the bottom or closed end of the barrel. The barrel, after having the gear ring 5 secured to it and the ball piece attached to its closed end, is inserted into the socket 14. When the ball 15 80 enters the socket 14, the ring 5 comes opposite the roller bearings 11, with the peripheral edge 6 of which they engage.

In order to rotate the barrel, causing mixing of its contents, I employ a bevel pinion 85 16 that engages with the bevel ring 5. It is mounted upon a shaft 17 that extends through one of the trunnions 7 and has secured to its outer end a wheel 18 through which the power is applied to turn the shaft, 90 a crank handle 19 being used for this purpose when the machine is to be hand-operated, as it ordinarily will be.

20 indicates a bar secured to the tilting frame for recking it on its trunnions 7, and 95 tilting the barrel. This bar is associated with means, indicated at 21, for locking it in different positions so that the barrel may be securely held, it being usual to provide for locking it in three positions, one with 100 the barrel with its discharge end upwardly inclined for mixing, another with the barrel substantially horizontal for loading, and a third with its discharge end downwardly inclined for delivering its contents. Thus in 105 Fig. 1 the position the barrel will occupy while being rotated for causing mixing is indicated by dot-and-dash lines, that which it occupies for discharging its contents by dotted lines, while full lines represent it as 110 having its axis of rotation horizontal—a position well adapted for charging the

barrel. The interior wall of the barrel will be provided with suitable agitating or mixing attachments as may be found desirable.

The mixing vessel that I prefer to use in a machine such as I have described is an ordinary wooden barrel. The gear ring 5 is applied directly to the exterior of such barrel and performs three offices; it strengthens the barrel near its middle portion; it constitutes the gear ring through which power is applied for rotating the mixing vessel; and it also serves as a bearing for the rollers, which therefore run upon a fairly true and cylindrical surface and do not engage with the surface of the barrel itself, which is more or less irregular and which in use would become rapidly worn.

By making the ring member of the supporting yoke of the two parts 9 9' separated so as to be on opposite sides of the gear ring 5, I arrange for easily supporting the rollers 11 so that they engage directly with the ring 5, and make it possible to adjust them radially to insure proper contact with the surface 6 of the gear ring. This adjustment may be effected by the use of liners 21 interposed between the brackets 10 and the ring members 9 9'.

The crossbar 13, that carries the socket member of the ball-and-socket joint at the closed end of the mixing vessel 4, is adjustably connected with the yoke members 12 12' to which it is united so that the two parts, the ball member 15 and the socket 35 into which it sets, may be easily brought into proper relationship before the crossbar carrying the socket member is finally secured in place by means of the nuts 23.

By making the rear extension of the supporting yoke of the two parts 12 12' separated as shown, and carrying the crossbar 13, the adjustment just described, and the ready assembly of the members of the ball-and-socket support are facilitated.

45 A mixing machine constructed as de-

scribed and as illustrated in the drawings may be made at relatively low cost, is not liable to get out of order, is substantial in construction and may be easily operated by one man. The mixing barrel or drum may be rotated, whatever its inclination incident to the adjustment of the tilting frame in which it is mounted, the drum being well balanced, due to the location of the bearings and the driving ring, as described and illustrated.

What I claim is:

1. In a mixing machine, a supporting frame, a rotatable mixing receptacle to the exterior of which is secured a bearing ring, 60 a tilting frame in which is situated the mixing vessel, mounted in the supporting frame and comprising a pair of rings surrounding the mixing vessel adjacent to the said bearing ring and spaced apart so as to lie on 65 opposite sides thereof, brackets secured to the peripheries of and uniting the said rings, rollers supported in the brackets and extending between the rings of the tilting frame and into engagement with the bearing 70 ring, and means for rotating the mixing vessel.

2. In a mixing machine, a rotatable mixing vessel, a tilting frame comprising a ring portion within which the mixing vessel lies 75 and turns, and a yoke extending across the closed end of the vessel, bearings mounted in the said ring for supporting the mixing vessel, a ball-and-socket bearing uniting the closed end of the vessel with the yoke and 80 disposed approximately on the axis of rotation of the mixing vessel, means for adjustably uniting one member of the said ball-and-socket bearing with the yoke portion of the tilting frame whereby the parts 85 of the said bearing may be easily brought into proper relationship after the mixing vessel is placed in the tilting frame, and means for rotating the vessel.

BENJ. S. REYNOLDS.
